FLUID PUMP CONTROL

Llewellyn W. Shelly, Allentown, Pa., assignor to
 The Aldrich Pump Company, Allentown, Pa., a
 corporation of Pennsylvania

Application February 12, 1938, Serial No. 190,285

11 Claims. (Cl. 103—40)

This invention relates to improvements in devices for loading and unloading piston pumps in fluid pressure systems, and more particularly to devices of this character adapted to function automatically to maintain said pressure between predetermined limits, or, as in the case where said system includes an accumulator, to maintain the fluid in the accumulator between given maximum and minimum volumes.

The principal object of the invention is to provide improved means for automatically loading and unloading a piston pump in synchronism with the movements of the pump pistons so that the loading and unloading operations may occur on the suction stroke or at any desired point in the suction strokes of the pistons.

The invention further resides in the novel apparatus and details of mechanism hereinafter described by which the aforesaid principal object and other useful ends, hereinafter set forth, are attained.

In the attached drawings:

Figure 1 is a side elevational view of a triplex power pump equipped with control means made in accordance with my invention;

Fig. 2 is a section on the line 2—2, Fig. 1;

Fig. 3 is an enlarged side elevational and partial sectional view of the control unit including a diagram of the associated electrical system;

Fig. 4 is a fragmentary sectional view illustrating the structural details of one of the elements of the mechanism;

Fig. 5 is a section on the line 5—5, Fig. 3;

Fig. 6 is a section on the line 6—6, Fig. 3;

Fig. 7 is a diagrammatic view illustrating the pressure system of the control device;

Fig. 8 is a fragmentary elevational and partial sectional view of a modified control mechanism within the scope of my invention including a diagram of the associated electrical system, and

Fig. 9 is a diagrammatic view of the pressure system of the control device illustrated in Fig. 8.

With reference to Figs. 1 and 2 of the drawings, I have therein illustrated for the purpose of describing the invention a triple cylinder pump comprising the usual frame 1, cylinder block 2, and crank shaft 3, the latter being continuously operated from a suitable source of power through a pulley 4. The shaft 3 comprises three cranks set apart at angles of 120°, and from these cranks piston rods 5 extend downwardly to pistons or plungers, 6, 7 and 8 respectively, which as shown in Fig. 2 operate in cylinders 9 in the block 2. Fluid is conducted

5 to the cylinders 9 through an intake pipe 11 and a manifold 12, which in the present instance is formed in the block 2. From the manifold 12 a passage 13 extends to each of the cylinders 9, and each of these passages 13 is controlled by a spring-tensioned check valve 14 which permits flow of fluid through the passage 13 to the cylinder, but normally prevents a reverse flow. From each of the cylinders 9 a discharge passage 15 extends to a manifold 16, and thence to a discharge pipe 17, and the connection between each of the individual passages 15 and the manifold 16 is controlled by a spring-tensioned check valve 18 which permits flow of fluid from the cylinder to the manifold, but prevents flow in the reverse direction. In the normal operation of a pump of this type, when one of the plungers is moving upwardly on the suction stroke, fluid is drawn into the cylinder past the valve 14, and is discharged from the cylinder on the downward or pressure stroke of the piston through the valve 18.

20 Mounted on the block 2 below each of the suction valves 14 is a pressure cylinder, 21, 22 and 23, respectively. As shown in Fig. 2, each of these cylinders contains a piston 24 from which a rod 25 extends upwardly through the manifold chamber 12 to the underside of the valve 14. When the plunger 24 is at the top of the cylinder 21 as shown in Fig. 2, the rod 25 by engagement with the under side of the valve 14, which has previously been lifted by suction on an upward movement of the plunger 6, prevents the valve from closing on the downward or pressure stroke of the plunger, with the result that fluid drawn into the cylinder 9 on the suction stroke of the plunger will be forced back through the passage 13 to the manifold 12. When the valve 14 is held open on the pressure stroke of the piston 6 as described, the valve 18 remains closed, and accordingly no fluid passes to the discharge 17. Springs 26 tend to force the pistons 24 to the bottoms of the associated cylinder 21, 22 and 23, in which position the rod 25 is depressed sufficiently to permit the suction valves 14 to close.

25 From the bottom of each of the cylinders 21, 22 and 23, a pipe, 27, 28 and 29, respectively, extends to a distributing valve 31. This valve, as shown in Fig. 3, comprises a casing 32 having formed in the upper end thereof three chambers, 33, 34 and 35, with which the pipes 27, 28 and 29 respectively, communicate. Each of the chambers 33, 34 and 35 communicates by means of a port 36 in its bottom wall with a manifold

chamber 37, and each of the ports 36 is controlled by a poppet valve 38. The stem 39 of each of the valves 38 extends downwardly to a tappet 41 which engages the surface of a cam, 42, 43 and 44, respectively, secured to a shaft 45, and this shaft, as indicated in Figs. 1 and 2, is connected with the crank shaft 3 of the pump and rotates with the latter. Each of the valve stems 39 is provided with a spring 40 which forces the rod downwardly upon the tappet 41 and holds the tappet against the face of the associated cam. The cams 42, 43 and 44 are arranged on the shaft 45 so that they will unseat the respective associated valves 38 in succession and at uniformly spaced intervals during one complete revolution of the shaft 45. There is also a direct relation between the positions of the cams 42, 43 and 44 and the positions of the cranks of the shaft 3 that produces a synchronized action, hereinafter described, between the plungers 6, 7 and 8 and the respective cams 42, 43 and 44.

From the manifold chamber 37 a pipe 46 extends to a port 47 in a solenoid-actuated valve 48. The port 47 is adapted to be connected through a valve element 49 with a pipe 51 extending to a source of fluid supply, as herein-after set forth. The valve 49 in a depressed position, as shown in Fig. 4, connects the pipe 51 with the port 47, so that the pipe 51 is in direct communication through said port with the pipe 46 and the manifold chamber 37 of the distributor valve 31. When the valve 49 is elevated, the connection between the pipe 51 and the port 47 is broken. The valve is operatively connected through a stem 52 and a link 53 with one end of a lever arm 54 which is pivotally mounted at 55 on the casing of the valve 48. A spring 56 connected to the same end of the lever 54 tends to hold that end of the lever in a depressed position, as shown in Fig. 4, in which position the valve 49 establishes communication between the pipe 51 and the port 47. The opposite end of the lever 54 is connected through a link 57 with the movable core 58 of a solenoid 59, and this solenoid when energized draws the core 58 downwardly from the extended position in which it is shown in Fig. 4, and thereby elevates the valve 49 to disconnect the pipe 51 from the port 47.

Attached to the lever 54 on the solenoid side 50 of the pivot 55 is a valve 61 which controls the connection between the port 47 and an exhaust pipe 62. When the solenoid 59 is deenergized and the spring 56 pulls the opposite end of the lever downwardly, as shown in Fig. 4, the valve 61 is drawn upwardly to its seat, thereby shutting off the exhaust pipe 62 from the port 47. When, on the other hand, the solenoid is energized, the valve 61 is moved downwardly from its seat, thereby connecting the port 47 with the pipe 62 and also, as previously described, drawing up the valve 49 to break the connection between the supply line 51 and the port 47. Under these circumstances, it will be apparent that the pipe 46 is directly connected through the port 47 with the exhaust pipe 62.

The electrical system, of which the solenoid 59 forms part, is illustrated in Fig. 3. In this system, as illustrated, electrical energy is supplied through line wires L¹ and L². The solenoid is adapted to be connected to the line wires L¹ and L² through the wires S¹ and S², this connection of the solenoid with the source of current being controlled by a magnetic switch M. The mag-

netic actuator of the switch M may be energized to close the solenoid circuit by means of switch F, which when closed forms a circuit comprising wires C¹, C² and C³. The switch F is normally open, but when momentarily closed effects a closing of the magnetic switch M and an immediate energization of the solenoid 59. Closing of the magnetic switch M, in addition to energizing the solenoid circuit, also closes a circuit comprising the wires C¹, C², H¹, unloading switch H², a wire H³ and a wire H⁴, this circuit including the magnetic switch actuator and acting as a holding circuit to maintain the switch M closed after switch F has been released or opened. After momentary closing and subsequent release of switch F, therefore, the magnetic switch will remain closed to thereby maintain the solenoid 59 in energized condition. The solenoid circuit remains closed until the switch H² is opened by means hereinafter described, thereby breaking the holding circuit of the magnetic switch M and permitting that switch to open, as shown in Fig. 3. By reason of the broken circuit of the normally open switch F, subsequent closing of the switch H² will not effect an actuation and closing of the magnetic switch M, so that after the switch H² has been opened to break the holding circuit, the solenoid 59 will remain deenergized until switch F is again momentarily closed, or until loading switch L is closed by means hereinafter described. The switch L is an element of a circuit including C¹, C², T¹, timing switch T, T², T³ and C³. Assuming that the switch F remains open, it is apparent that closing of the switch L accompanied by a completion of the circuit through the timing switch T will effect an energization of the magnetic actuator of switch M and a reclosing of that switch with consequent reenergization of the solenoid 59. With the closing of the magnetic switch M, the holding circuit, which includes the unloading switch H² as described above, will retain the magnetic switch in the closed position even after the breaking of the circuit C¹, C², T¹, T², L, T³ and C³, so that in spite of the opening of this latter circuit either through the loading switch L or the timing switch T, the solenoid 59 will remain in the energized condition until a subsequent opening of the switch H².

It will be noted that loading of the pump may be accomplished either by momentarily closing the manual switch F, or by closing the switch L and holding this switch closed until the circuit has been completed at T. Unloading is effected either by the opening of the switch H², or by opening a normally closed manually actuated switch F², which may be of the push-button type and which is associated in the present instance with the switch F, the switch F² being in series with the switch H² as shown. The switches F and F² constitute a convenient means for manually controlling loading and unloading under all conditions, emergency or otherwise, and may be actuated to load or unload at any time as may be necessary or desirable.

The discharge 17 of the pump may be connected to a pressure system or vessel, and in the present instance to an accumulator 63, and the switches H² and L are arranged for actuation in accordance with the accumulator travel. When under loading conditions the accumulator by reason of the increasing quantity of contained fluid approaches the outer limit of its travel, the unloading switch H² is opened, but will immediately close when the volume of fluid in the accumu-

lator falls below the predetermined maximum. The switch L on the other hand, which as stated is a loading switch, is arranged to be closed when the accumulator, by reason of the decreasing volume of its contained fluid, approaches the other end of its travel, and this switch in turn will automatically reopen as soon as the volume of fluid in the accumulator increases above the predetermined minimum. In the present instance, I have indicated diagrammatically the actuation of the switches H² and L by mechanical connection with the moving element of the accumulator. When this element, indicated by the numeral 63, is elevated by an increasing quantity of fluid within the accumulator to the upper end of its predetermined travel, a cam 64 on the accumulator will engage the switch arm and open the switch. This same cam when the accumulator member has dropped by reason of withdrawals of fluid from the accumulator to the other end of its travel will engage the arm of the switch L, and will close that switch. Except when actuated by the cam 64, or by other means, the switch H² will be closed and the switch L open.

The operation of the device described above is as follows: As previously stated, when the solenoid 59 is deenergized and the elements of the associated valve occupy the positions shown in Fig. 4, fluid pressure admitted through the pipe 51, which latter pipe may be connected with the accumulator 63 or other source of fluid pressure, will be transmitted through the port 47 to the pipe 46, and through this pipe to the manifold chamber 37 of the distributor valve 31. This pressure admitted to the cylinders 21, 22 and 23 through action of the valves 38 and of the cams 42, 43 and 44 of the distributor valve will support the suction valves 14 of the pump cylinders in the open position, so that the pump in effect is unloaded and is prevented from feeding fluid to the accumulator 63. The solenoid 59 may now be energized to effect loading of the pump by momentarily closing the normally open push button switch F, thereby energizing and closing the magnetic switch M and completing the solenoid circuit as well as the holding circuit controlled, as hereinbefore described, by the unloading switch H². With the solenoid energized, the valve 49 is elevated to break the connection between the fluid supply pipe 51 and the port 47, and the valve 61 is opened to connect the pipe 46 through the port 47 with the exhaust 62, so that the manifold 37 is exhausted. The pressure being thus released from the cylinders 21, 22 and 23, the suction valves 14 of the pump will function in the normal manner. Fluid now flows into the accumulator until the volume reaches the predetermined maximum, at which time the switch H² is automatically opened, breaking the holding circuit of the magnetic switch M and permitting that switch to open, thereby again deenergizing the solenoid 59, disconnecting the manifold 37 from the exhaust, and connecting the manifold with the fluid supply admitted through the pipe 51. The pump now is unloaded, and it will be noted that by reason of the aforescribed arrangement of the cams 42, 43 and 44 of the distributor valve with respect to the cranks of the shaft 3 of the pump, fluid pressure is admitted to the cylinders 21, 22 and 23 successively and at the time that the pump piston 6 of the associated cylinder of the pump is on its upward or suction stroke. The pistons 24 of the cylinders 21, 22 and 23 are, therefore, elevated against negative pres-

sure in the pump cylinders, and no effort aside from that required to overcome the weight of the piston 24 and its stem 25 and the pressure of the springs 26 is required to elevate the pistons. In other words, the unloading of each of the cylinders of the pump occurs on the suction stroke of its associated plunger.

With the pump unloaded, passage of fluid to the accumulator by the pump is interrupted until such time as the fluid in the accumulator has been exhausted to the predetermined minimum amount, at which time the switch L is automatically closed as previously described. Closing of the switch L, however, does not necessarily complete the circuit through the magnetic actuator of switch M, it being necessary, in order that this circuit be completed, that the timing switch T shall have moved to one or other of its several circuit-closing positions.

Assume in Figs. 3 and 6 that the timing switch T consists of a cylinder 65 mounted on the shaft 45 and slidably engaged on its cylindrical surface by two brushes 66 and 67. In that portion of the circumference of the cylinder 65 engaged by the brush 66, the cylinder presents a continuous metallic surface, and in that portion of the cylinder engaged by the brush 67, the metallic surface of the cylinder is interrupted by three relatively spaced insulated areas 68, 69 and 70. The electric circuit is completed, therefore, only when the brush 67 engages the metallic surface of the cylinder between the insulated areas 68, 69 and 70. By arranging the cylinder 65 so that the said insulated portions occupy predetermined positions with respect to the cranks of the shaft 3, it is apparent that the closing of the circuit may be regulated to occur at any desired point in the suction strokes of the respective pump plungers. It is possible, therefore, to effect the loading of the pump or of the individual pump cylinders at the most advantageous point in the suction stroke of the pump plunger. This timing device controlling the electric circuit in conjunction with the cams 42, 43 and 44 affords a highly flexible regulation of the loading operation.

When, therefore, the switch L has been closed as described above and the circuit completed through the timing switch T to thereby energize and close the magnetic switch M, the resulting energization of the solenoid 59 will effect a loading of the pump cylinders, resulting in a building up of the fluid in the accumulator until such time as the maximum volume has again been attained. It will be noted in respect to the loading of the pump through closing of the switch L and operation of the timing switch T, that when the magnetic switch M has been closed through a completion of the loading switch circuit, the holding circuit including the switch H² which is now closed retains the magnetic switch closed until such time as the switch H² is opened, such opening occurring automatically when the volume of fluid in the accumulator has reached the predetermined maximum.

The embodiment of my invention shown in Figs. 8 and 9 of the drawings operates on essentially the same principle as the embodiment previously described, but differs from that embodiment in that control of the loading and unloading operations resides entirely in the electrical system. To simplify description, the various elements of the pump mechanism and of the electrical control system corresponding to the elements of the embodiment shown in Fig. 3, are identified by the same reference numerals. In

this instance, I employ three solenoid valves, corresponding in form and operation to the valve 48 of the preceding embodiment, to directly control the flow of fluid pressure through the pipe 51 to the cylinders 21, 22 and 23, (the two first-named of these cylinders not being shown in the drawings) which constitute the means for supporting the suction valves 14 of the pump cylinder in unseated position. The three solenoid valves, designated 48a, 48b and 48c, when deenergized, connect the respective cylinders 23, 21 and 22 with the supply pipe 51 through the pipes 14, 12 and 13, respectively, and thereby effect the unloading of the pump as described above. When energized, the cylinders 21, 22 and 23 are connected through the same pipes 12, 13 and 14, respectively, with the exhaust pipes 15, 16 and 17, and the pump is thereby unloaded.

Each of the solenoid valves 48a, 48b and 48c is adapted to be connected individually with a source of electrical energy through the line wires L¹ and L², and each of these individual connections of the solenoid valves is controlled by a magnetic switch, M¹, M² and M³, respectively. Flow of current to the magnetic switches and through these switches to the solenoid valves 48a, 48b and 48c is controlled, as in the previous embodiment, by the unloading and loading switches H² and L, respectively, which are arranged for mechanical actuation by the accumulator as previously described. The unloading switch H² in the present instance is located in one of the line wires L¹, and the loading switch L is shunted by a circuit which includes the push button switch F adapted for manual actuation.

The timing of the energization of the solenoid valves 48a, 48b and 48c in synchronism with the movements of the pistons in the pump cylinders, so that actuation of these valves for loading occurs during the suction strokes of the respective pistons, is effected by means of a timer 66a carried by a shaft 45 connected with the crank shaft of the pump. This timer is of the general character of that previously described above in connection with the preceding embodiment, but comprises in this case four brushes, 78, 79, 80 and 81, the brushes 79, 80 and 81 being associated respectively with the magnetic switches M¹, M² and M³. The timer cylinder with which the brushes contact is provided with a plurality of contact elements 82, 83, 84, 85 and 86. The brushes 82 and 83 are arranged in alignment so that when the contact 82 meets the brush 78, the contact 83 will simultaneously meet the brush 81, and the contacts 82 and 83 are electrically connected so that these contacts may complete a circuit between the said brushes 78 and 81. Similarly the contact 84 is of a width sufficient to simultaneously engage the brushes 78 and 79, so that when this contact meets these last-named brushes a circuit is completed therebetween. The contacts 85 and 86 are electrically joined and are arranged on the timer cylinder so that when the contact 85 meets the brush 78, the contact 86 at the same time meets the brush 80. The contacts 82-83, 84, and 85-86 are arranged in spaced relation around the timer cylinder at intervening angles of 120°.

Assuming that the pump is unloaded and that the various switches of the electrical system are as shown in the drawings, the solenoid valves 48a, 48b and 48c are now deenergized, thereby admitting fluid pressure from the supply 51 to the cylinders 21, 22 and 23, and elevating the rods 25 to maintain the suction valves 14 of the pump in

the elevated or open position. Loading of the pump can now be accomplished by closing the switch L or by a manual closing of the push button switch F, which as previously stated is established in a circuit shunting the switch L. When either of these switches is closed and the contact 84 of the timer meets the brushes 78 and 79, a circuit is formed from L¹ to L², which includes C⁴, actuator of magnetic switch M¹, C⁵, C⁶, L or F and C⁷ to L². Energization of the magnetic actuator of switch M¹ closes that switch and thereby completes a circuit from L¹ through C⁴, the actuator of the switch M¹, C⁵, H⁵, H⁶, H⁷ and H⁸ to L². This is a holding circuit which maintains the magnetic actuator of M¹ in energized condition when and after the switch F or L, as the case may be, is opened. Closing of the magnetic switch M¹ completes the circuit from L¹ through C⁴, S³, S⁴, and H⁸ to L², thereby energizing the solenoid valve 48a and connecting the pipe 14 of the cylinder 23 with the exhaust pipe 17, at the same time interrupting the flow of fluid from the pipe 51 through the valve. Escape of fluid from the cylinder 23 permits the spring 26 to depress the rod 25, thereby leaving the suction valve 14 free to close. Owing to the position of the contact 84 with respect to the pump crank shaft, energization of the solenoid valve 48a and the consequent release of pressure in the cylinder 23 occurs on the suction stroke of the piston of the pump with which the said cylinder 23 and the related suction valve is associated. When the timer cylinder 66a is advanced through an angle of 120°, the solenoid valve 48b is similarly energized, and an additional advance of 120° of the timer 66a results in an energization of the solenoid valve 48c. In each case, the energization of the valve occurs on the suction stroke of the associated plunger of the pump. When the brushes 78 and 80 are connected through the contacts 85 and 86 of the timer, an electrical circuit is completed from L¹ through C⁸, magnet M², C⁹, C¹⁰, switch F or L, C⁷ to L². The magnetic switch M² being thereby closed, a holding circuit for that switch is established through C⁸, magnet M², C⁹, H⁸, H¹⁰, H⁷ and H⁸ to L², so that this switch will remain closed regardless of the opening of the switch L or the switch F, or the further movement of the timer 66a. When the contacts 82 and 83 of the timer engage the brushes 78-81, a circuit is made from L¹ through C¹⁰, magnet M³, C¹¹, C⁶, switch F or L, C⁷ to L². Resulting closing of the magnetic switch M³ establishes a holding circuit through C¹⁰, magnet M³, C¹¹, H¹¹, H¹², H⁷ and H⁸ to L².

The pump is now fully loaded, and this loading continues until such time as the unloading switch H² is opened by action of the accumulator or switch F² is opened manually. When this occurs, the magnetic switches M¹, M² and M³ are released, and the circuits of the solenoids 48a, 48b and 48c thereby broken, with the result that the pump is again unloaded. It is to be noted that in this case if the loading is effected through the manual push button switch F, this switch must be held closed until energization of all of the solenoid valves 48a, 48b and 48c is completed, this occurring in one full revolution of the shaft 45.

I claim:

1. The combination with a fluid system including a reciprocating fluid pump for supplying fluid thereto, of means for automatically loading and unloading said pump to maintain between

predetermined maximum and minimum limits the volume of fluid in said system, said means comprising a valve controlling said loading and unloading, a fluid motor for operating said valve, an electrically-actuated control valve for said motor, an electrically-actuated control switch for said valve, and an electric control system including an unloading switch adapted to be opened automatically when the volume of fluid in the system attains the said maximum and controlling flow of current to the actuator of said control switch, a loading switch adapted to be closed automatically when the volume of fluid in the system has decreased to the said minimum and controlling flow of current to the actuator of said control switch, a timing switch operating in synchronism with the pump and arranged in series with said loading switch to operate jointly with the latter to control flow of current to the actuator of said control switch, and a holding circuit for said control switch shunting said loading and timing switches and including a switch actuated simultaneously with and in the same phase as said control switch.

2. The combination with a fluid system including a multicylinder fluid pump for supplying fluid thereto, of means for automatically loading and unloading said pump to maintain between predetermined maximum and minimum limits the volume of fluid in said system, said means comprising a valve controlling the loading and unloading of each of said pump cylinders, a fluid motor for operating each of said valves, an electrically-actuated control valve for each of said motors, an electrically-actuated control switch for each of said valves, and an electric control system embracing said switches and including an unloading switch adapted to be opened automatically when the volume of fluid in the system attains said maximum and controlling flow of current to the actuators of said control switches, a loading switch adapted to be closed automatically when the volume of fluid in the system has decreased to the said minimum and controlling flow of current to the actuators of said control switches, timing switches operating in synchronism with the pump and arranged individually in series with said loading switch to operate jointly with the latter to control the flow of current respectively to the actuators of said control switches, and a holding circuit for each of said control switches shunting the respective timing switches and said loading switch and each including a switch actuated simultaneously with and in the same phase as the associated control switch.

3. The combination with a fluid system including a reciprocating fluid pump for supplying fluid thereto, of means for automatically loading and unloading said pump to maintain between predetermined maximum and minimum limits the volume of fluid in said system, said means comprising a valve controlling said loading and unloading, a fluid motor for operating said valve, an electrically-actuated control valve for said motor, an electrically-actuated control switch for said valve, a timing valve controlling the operation of said motor jointly with the electrically-actuated valve and operated in synchronism with the pump, and an electric control system including an unloading switch adapted to be opened automatically when the volume of fluid in the system attains the said maximum and controlling flow of current to the actuator of said control

5 switch, a loading switch adapted to be closed automatically when the volume of fluid in the system has decreased to the said minimum and controlling flow of current to the actuator of said control switch, a timing switch operating in synchronism with the pump and arranged in series with said loading switch to operate jointly with the latter to control flow of current to the actuator of said control switch, and a holding circuit for said control switch shunting said loading and timing switches and including a switch actuated simultaneously with and in the same phase as said control switch.

4. The combination with a fluid system including a multicylinder fluid pump for supplying fluid thereto, of means for automatically loading and unloading said pump to maintain between predetermined maximum and minimum limits the volume of fluid in the system, said means comprising a valve controlling the loading and unloading of each of said pump cylinders, a fluid motor for operating each of said valves, an electrically-actuated control valve for each of said motors, an electrically-actuated control switch for each of said valves, and an electric control system embracing said switches and including an unloading switch adapted to be opened automatically when the volume of fluid in the system attains said maximum and controlling flow of current to the actuators of said control switches, a loading switch adapted to be closed automatically when the volume of fluid in the system has decreased to the said minimum and controlling flow of current to the actuators of said control switches, timing switches operated in synchronism with the pump and arranged individually in series with said loading switch to operate jointly with the latter to control the flow of current respectively to the actuators of said control switches, and a holding circuit for each of said control switches shunting the respective timing switches and said loading switch and each including a switch actuated simultaneously with and in the same phase as the associated control switch.

5. The combination with a fluid system including a reciprocating fluid pump for supplying fluid thereto, of means for automatically loading and unloading said pump to maintain between predetermined maximum and minimum limits the volume of fluid in said system, said means comprising a valve controlling said loading and unloading, a fluid motor for operating said valve, an electrically-actuated control valve for said motor, means controlled by the fluid in said system for operating said valve to maintain said volume within predetermined limits, a timing valve controlling the operation of said motor jointly with the electrically-actuated valve and operated in synchronism with the pump, and means operated in synchronism with said pump for timing the operations of said electrically-actuated valve by said fluid-controlled means.

6. The combination with a fluid system including a reciprocating fluid pump for supplying fluid thereto, of means for automatically loading and unloading said pump to maintain between predetermined maximum and minimum limits the volume of fluid in said system, said means comprising a valve controlling said loading and unloading, a fluid motor for operating said valve, a primary valve controlling the operation of said motor and means for automatically actuating said valve when the said fluid volume in the system approaches either of said limits, a secondary

valve and means for actuating said valve in timed relation with the operation of the pump, said secondary valve being operative to synchronize the motor operations with the operation of said pump, and means also operated in timed relation with the pump for synchronizing operation of said primary and secondary valves.

7. The combination with a fluid system including a reciprocating fluid pump for supplying fluid thereto, of means for automatically loading and unloading said pump to maintain between predetermined maximum and minimum limits the volume of fluid in said system, said means comprising a valve controlling said loading and unloading, a motor for operating said valve, primary means actuated automatically when the said fluid volume in the system approaches either of said limits for controlling the operation of said motor, secondary motor control means actuated in timed relation with the operation of the pump and operative to synchronize the said motor and pump operation, and means also operating in timed relation with the pump for synchronizing operation of said primary and secondary control means.

8. The combination with a fluid system including a piston pump for supplying fluid thereto, of means for automatically loading and unloading said pump to maintain the volume of fluid in said system between predetermined maximum and minimum limits, said means comprising a valve controlling said loading and unloading, a fluid-actuated piston for operating said valve, a valve controlling the operation of said piston, said valve being adapted in alternative positions of adjustment to permit passage of fluid to and from the piston respectively, one for loading and the other for unloading the pump, means for automatically moving said valve into said alternative positions respectively when the said fluid volume in the system approaches said limits, a second valve controlling passage of fluid to and from the piston and operating in timed relation with the pump for synchronizing the actuations of said motor with the movements of the pump piston, and means also operated in timed relation with the pump for synchronizing the operation of said valves in loading the pump.

9. The combination with a fluid system including a piston pump for supplying fluid thereto, of means for automatically loading and unloading said pump to maintain the volume of fluid in said system between predetermined maximum and minimum limits, said means comprising a valve controlling said loading and unloading, a fluid-actuated piston for operating said valve, a valve controlling the operation of said piston, said valve being adapted in alternative positions of adjustment to permit passage of fluid to and from the piston to unload and load the pump

respectively, means for automatically adjusting said valve into position to admit fluid to the piston when the said fluid volume in the system approaches the maximum limit and for automatically adjusting the valve into the other of said alternative positions when the fluid volume in the system approaches the minimum limit, a second valve controlling passage of fluid to and from the piston and operating in timed relation with the pump for synchronizing the actuations of said motor in loading and unloading the pump with the movements of the pump piston, and means also operated in timed relation with the pump for synchronizing the operation of the one valve with the other in the loading operation.

10. The combination with a fluid system including a reciprocating fluid pump for supplying fluid thereto, of means for automatically loading and unloading said pump to maintain the volume of fluid in said system between predetermined maximum and minimum limits, said means comprising a valve controlling said loading and unloading, a fluid motor for operating said valve, an electrically-actuated primary valve controlling the operation of said motor, and means for automatically actuating said valve when the said fluid volume in the system approaches either of said limits, a secondary motor-control valve and mechanical means for actuating said valve in timed relation with the operation of the motor, said secondary valve being operative to synchronize the motor operations with the operation of said pump, and electrical control means for said primary valve operating in timed relation with the pump to synchronize operations of said primary and secondary valves.

11. The combination with a fluid system including a multicylinder piston pump for supplying fluid thereto, of means for automatically loading and unloading said pump to maintain the volume of fluid in said system between predetermined maximum and minimum limits, said means comprising a valve controlling the loading and unloading of each of the pump cylinders, a fluid-actuated piston for operating each of said valves, a primary valve common to all of said pistons for controlling the passage of fluid to and from the latter, means for automatically actuating said valve when the said fluid volume in the system approaches either of said limits, a distributing valve operating in timed relation with the operation of the pump for controlling the passage of fluid to and from said pistons individually and for synchronizing the operation of each of said pistons with the associated pump piston, and means also operated in timed relation with the pump for synchronizing operations of said primary and distributing valves.
